(57) **CLAIM**

The ornamental design for a phone case, as shown and described.

DESCRIPTION

FIG. 1 is a perspective view including a rear, top and one side of the phone case;

FIG. 2 is a perspective view including a rear, bottom and one side of the phone case;

FIG. 3 is a perspective view including a front, top and one side of the phone case;

FIG. 4 is a perspective view including a front, bottom and one side of the phone case;

FIG. 5 is an elevational view of the front of the phone case of FIG. 1;

FIG. 6 is an elevational view of the rear of the phone case of FIG. 1;

FIG. 7 is an elevational view of the opposite side of the phone case of FIG. 1;

FIG. 8 is an elevational view of the side of the phone case of FIG. 1;

FIG. 9 is a plan view of the top of the phone case of FIG. 1;

FIG. 10 is a plan view of the bottom of the phone case of FIG. 1; and,

FIG. 11 is an enlarged detail view of the encircled portion of FIG. 3.

The dot-dash broken lines in FIGS. 3 and 11 delineate a portion of the claimed design that is shown on an enlarged scale in FIG. 11. The dot-dash broken lines form no part of the claimed design.

1 Claim, 9 Drawing Sheets
